JOURNAL LUBRICATOR

Frederick W. Martin, Greenwich, Conn.

Application December 18, 1941, Serial No. 423,456

5 Claims. (CL 308—88)

This invention relates to means for lubricating the journals of railway vehicle axles and is especially applicable to that type of equipment wherein a crown bearing is employed and the lubrication is applied to the under side of the journal.

The principal object of the invention is to provide an improved journal lubricating means which will completely overcome the difficulties heretofore incident to the employment of the customary waste, which waste, as is well known, tends to settle away from the journal due to steady vibration during service. Also in cold weather the waste tends to freeze to the journal, so that small portions thereof are torn away and drawn into the bearing where they gradually accumulate and cause hot boxes. Furthermore, at short intervals the box must be opened, the waste loosened, and oil added which is troublesome, time-consuming and expensive.

More specifically stated, the objects of the invention are the provision of means for automatically lubricating the journal without the use of the customary waste or the employment of any moving parts such, for example, as have been employed heretofore with various pumping or other mechanical mechanisms for positively forcing the lubricant against the journal; the provision of a lubricating means which will reduce the consumption of oil; the provision of a lubricating mechanism in which an absorbent or wick-like pad member is employed for conveying the lubricant from the reservoir to the journal; the provision of means for avoiding glazing of the pad; and the provision of a lubricating mechanism of the character described in which the lubricant is very simply and effectively retained in the reservoir below the journal without the necessity for any special packing for this purpose.

It is also an object of my invention to provide a lubricating mechanism which can be adapted for use either in locomotive driving boxes or in the customary journal boxes of railway cars.

How the foregoing objects, together with any other objects which are incident to my invention or which may appear hereinafter, are attained, is illustrated in preferred forms in the accompanying drawing wherein—

Figure 1 is a vertical cross section through a locomotive driving box equipped with my improvements;

Figure 2 is a vertical longitudinal section of the lubricating structure by itself; and

Figure 3 is a vertical longitudinal section through an embodiment of my invention which is particularly adapted for use in the journal boxes of railway car axles.

5 Figures 1 and 2 show the invention as applied to a locomotive driving box, and these figures will be described first. The driving box 4 is provided with the crown bearing 5 in which the journal of the driving axle 6 is adapted to rotate. Beneath the journal and between the sides 7 of the box is located the oil reservoir 8 which is held in place by the pins 9 extending through downwardly projecting opposed lugs 10.

15

The reservoir is provided with arcuate end portions or plates 11 and 12 and upstanding rectangular side portions 13, all of which co-operate to form a chamber or reservoir for the oil 14.

20

A journal contacting plate 15 is fitted into the upper portion of the reservoir, which plate may be curved either in whole or in part to fit the curvature of the journal. In the embodiment illustrated I have shown the entire plate as being curved upon a radius which fits it snugly against the under face of the journal. This plate is provided with a series of perforations 16 which may extend from the bottom portion upwardly and outwardly around the circumference of the journal to whatever distance may be necessary or desired. In the embodiment illustrated I have shown these perforations as extending over approximately the bottom third of the plate 15.

25

30

35

At its ends the plate is provided with the downwardly extending lip portions 17 and at its sides with the downwardly extending longitudinal flange portions 18, the latter of which are adapted to take against the sides 13 of the reservoir in order to prevent the plate from being dragged around under the influence of the rotary motion of the journal.

40

45

At each side the plate 15 is also provided with the longitudinally extending journal wiping pads 19 which are mounted upon suitable resilient supporting arms 20 connected to the sides 18 of the plate. These pads serve to wipe off any excess oil and permit it to drip back into the reservoir, return of the oil in this manner being facilitated by the holes 18a in the turned upper side portions of the plate, as shown in Figure 1.

50

Beneath the journal contacting plate 15 is a follower plate 21 which is curved to correspond to the curvature of the plate 15 but on a radius

55

which is somewhat greater than the radius of the curvature of the plate 15 and from a center which lies beyond the center of curvature of the plate 15 for a purpose which will appear hereinafter. The follower plate is rounded over at the sides 21-22 so as not to cut or damage the pad member to be subsequently described.

The follower plate is supported upon and urged upwardly toward the plate 15 and the journal by means of a plurality of suitable spiral springs 23 which are secured at their upper ends to the bottom of the plate 21 by means of rivets 24. At their lower ends they fit around the bosses 25 which project upwardly from the bottom of the reservoir.

Between the two plates I provide the absorbent pad or wick-like member 26 which has its marginal portions curved downwardly to provide the substantially continuously extending skirt portion 27 which projects into the oil in the reservoir and which is constructed and arranged in relation to the plate 21 so as to fit rather closely against the sides and ends 13 and 14 of the reservoir 8. By so forming and arranging the pad it acts as a very efficient lubricant retaining member because it encloses the main body of the oil in the reservoir and prevents losses which would otherwise occur due to the splashing action set up during motion of the vehicle. In fact, it is so efficient for this purpose that it completely eliminates the necessity for any other packing means. The consumption of lubricant is thereby reduced because none is lost or wasted, and that which is used is only that which is normal to the operation of the lubricator, and this, of course, is directly in proportion to the degree and speed of journal rotation. The supply of lubricant may be replenished by removing the screw plug 28.

The plate 15, the pad 27, the plate 21 and the supporting springs 23 constitute a lubricating unit which, if desired, may be secured together for convenience in handling. This may be accomplished in any one of a number of ways, that which is illustrated being as follows. The rivets 24 hold the pad 26 to the follower plate 21 and the springs 23 to the under side of the plate 21. The upper or journal contacting plate 15 is stitched to the pad 26 as at 29, although rivets may be employed for this purpose also, providing of course that they are arranged so that their heads or ends do not injure the surface of the journal.

In adapting the invention for use with car axle journals in the customary axle or journal box, I prefer the modification illustrated in Figure 3. In this view the box is shown at 30 and the axle with its journal at 31 and 32 respectively, the latter being provided with the customary end collar 33. The journal box lid is shown at 34, and because of the fact that under normal conditions the box and the journal are never separated, I have made the lubricating mechanism per se so that it can be flexed for insertion into or removal from the box, as indicated in dotted lines in this figure.

The structure of this flexible mechanism is as follows. The journal contacting plate is composed of a plurality of individual sections 15a which are curved as in the case of the plate 15 to fit the under side of the journal. They are also provided with perforations 16a which may extend for a greater or less distance from the bottom outwardly and upwardly, as before indicated. The abutting edges 35 of the plates 15a

are cut back so as to form a V-shaped opening between each plate, as clearly shown in the figure. They may be secured to the pad 26a in a manner similar to that employed for the plate 15 and the pad 26 or by means of rivets as described below. The pad is provided with the downwardly extending skirt portion 27a which, as before, acts as a lubricant retaining member as well as a feeding wick for the oil.

10 The follower plate is similarly formed as a plurality of individual pieces 21a which also are cut back at their adjacent edges in order to form the V-shaped openings 36. Each section is provided with a supporting spring 23a the upper ends of which are secured to the under side of the follower plate by means of the rivets 24a, the latter acting also as a means for securing the pad and the two plates together to which purpose the rivet holes in the journal contacting plate should be countersunk, as shown, so as to avoid damage to the journal. The lower ends of the springs 23a are fastened to the spring steel strip 37 which rests on the bottom of the box, and as previously described, this whole lubricating mechanism per se can be flexed upwardly for insertion into or removal from the box past the lower portion of the collar 33, as indicated roughly by dotted lines, the V-shaped openings between the plates permitting the necessary degree of articulation for this operation. Of course, other means for articulating the parts may be employed, but I have found this to be satisfactory in service.

15 It should also be pointed out that in the arrangement of Figure 3 the follower plate 21a is curved to correspond to the curvature of the plate 15a with the curvature, however, being on a greater radius than the radius of the plate 15a and from a center lying beyond its center of curvature.

20 It is believed that the operation of my improved lubricator will be clearly apparent from the description given, but it is desired to point out that the difference in curvature between the two plates permits the wick-like pad member to fluff up slightly as it approaches the sides of the box so that there is never any undue pressure on any portion of the pad which would interfere with its ability to carry the oil upwardly from the reservoir. The only real pressure which is exerted upon it is applied at the middle at the lowermost point under the journal just above the springs, but at this point the oil has traveled as far as it is necessary for it to travel through the wick-like fibers of the pad.

25 When the vehicle is in motion the rotation of the journal acts to create a slight vacuum in the perforations in the journal contacting plate, which vacuum of course tends to draw the oil upwardly out of the pad and against the face of the journal, the journal, in turn, carrying the lubricant to the under side of the crown bearing in a manner well understood in this art.

30 The journal contacting plate prevents all glazing of the upper surface of the pad such as has been troublesome in previous pad lubricators where the pad was placed in direct contact with the journal. The constant rubbing of the journal against these pads very quickly develops this glazed condition and interferes with proper lubrication. Furthermore, with the old style arrangements, using either waste or directly contacting pads, it was often found that the fibers froze to the journals in excessively cold weather, which caused lint-like particles or short ends to be torn

from the mass and carried on the journal to the under side of the bearing where they accumulated and frequently caused hot boxes. All troubles of this kind are completely eliminated with my improved device.

It can readily be appreciated that by eliminating the customary waste or the employment of any pumps or any mechanically moving parts, I have provided an oil lubricator of extreme simplicity and durability and one which can be very economically maintained in service because it requires much less frequent inspection, repairs and so forth than any other lubricator with which I am familiar. Furthermore, its consumption of oil is exceedingly low while the efficiency of lubrication is greatly increased.

I claim:

1. Lubricating means for the journal of a railway vehicle axle, said means including an oil reservoir under the journal, a plate having a relatively extended portion thereof curved to fit and contact with the journal, perforations in said curved portion, an absorbent wick-like pad member below said plate, a follower plate below said pad member curved to correspond generally to the curvature of the journal contacting plate but on a greater radius, said plates normally being arranged to provide a gradually increasing distance therebetween from the low point beneath the journal outwardly and upwardly toward each side of the journal, marginal portions on said pad member arranged to hang downwardly from the follower plate and adapted to project into the oil in the reservoir, and means for urging the follower plate toward the journal plate to support said pad member in contact with the perforated plate, all of said parts being constructed and arranged to permit the side portions of said pad member to

"fluff" up slightly under normal service conditions.

2. A railway axle journal lubricating unit for use in a journal box oil reservoir, said unit including a plate having a relatively extended portion thereof curved to fit and contact with the journal, perforations in said curved portion, an absorbent wick-like pad member below said plate, a follower plate below said pad member curved to correspond generally to the curvature of the journal contacting plate but on a greater radius, said plates normally being arranged to provide a gradually increasing distance therebetween from the low point beneath the journal outwardly and upwardly toward each side of the journal, marginal portions on said pad member arranged to hang downwardly from the follower plate and adapted to project into the oil in the reservoir, and resilient supporting means secured to the under side of said follower plate, all of said parts being constructed and arranged to permit the side portions of said pad member to "fluff" up slightly under normal service conditions.

3. The structure of claim 1 wherein the pad-like member has its downwardly projecting portions formed as a substantially continuous skirt which is adapted to substantially enclose the oil in the reservoir.

4. The structure of claim 1 wherein the journal contacting plate carries a journal wiping pad for each side of the journal, said wiping pads being resiliently supported to press against the journal at points above the side edges of the contacting plate.

5. The structure of claim 1 wherein the journal contacting plate is provided with a reservoir engaging flange at each side thereof.

FREDERICK W. MARTIN.
